(57) **CLAIM**

The ornamental design for a stool, as shown and described.

DESCRIPTION

FIG. 1 is a perspective view of a stool in accordance with a first embodiment of the inventive design;

FIG. 2 is another perspective view of the stool as seen in FIG. 1;

FIG. 3 is a front view of the stool as seen in FIG. 1; rear, left and right views being identical;

FIG. 4 is a front and right side view of the stool as seen in FIG. 1; front and left, rear and right and rear and left views being identical;

FIG. 5 is a top view of the stool as seen in FIG. 1;

FIG. 6 is a bottom view of the stool as seen in FIG. 1;

FIG. 7 is a perspective view of a stool in accordance with a second embodiment of the inventive design;

FIG. 8 is another perspective view of the stool as seen in FIG. 7;

FIG. 9 is a front and right side view of the stool as seen in FIG. 7; front and left, rear and right and rear and left views being identical;

FIG. 10 is a front view of the stool as seen in FIG. 7; rear, left and right views being identical;

FIG. 11 is a top view of the stool as seen in FIG. 7;

FIG. 12 is a bottom view of the stool as seen in FIG. 7;

FIG. 13 is a perspective view of a stool in accordance with a third embodiment of the inventive design;

FIG. 14 is another perspective view of the stool as seen in FIG. 13;

FIG. 15 is a front view of the stool as seen in FIG. 13; rear, left and right views being identical;

FIG. 16 is a front and right side view of the stool as seen in FIG. 1; front and left, rear and right and rear and left views being identical;

FIG. 17 is a top view of the stool as seen in FIG. 13; and,

FIG. 18 is a bottom view of the stool as seen in FIG. 13.
